MARKING MACHINE

Laurits Andersen, Boston, Mass., assignor to
T. J. Edwards, Inc., Boston, Mass., a corpora-
tion of Massachusetts

Application June 8, 1938, Serial No. 212,471

1 Claim. (Cl. 101—298)

The present invention relates to machines of the type in which a properly shaped applying die impresses material on a previously positioned piece of work. As disclosed in the Edwards 5 Patents No. 1,796,686, March 17, 1931, and No. 2,113,684, April 12, 1938, the material impressed upon the work may be ink or cement. In the machines disclosed in these patents, the applying die is mounted on a carrier provided with an 10 operating handle which is manipulated by the operative to swing the carrier from a position where the die picks up the material to a position where the die deposits the material upon the work. These dies have become complicated 15 and, in consequence, it has been difficult heretofore for the operative, usually a girl, to exert sufficient pressure through the operating handle to impress the die properly on the work. It has been proposed heretofore to provide this type of 20 machine with a treadle operated mechanism, but it proved unsatisfactory and made no impression in the art commercially, principally because it required the use of one pedal to swing the die to a position where it picked up the material 25 and another pedal to swing the die to a position where it deposited the picked up material upon the work.

The principal objects of the present invention are to produce a machine of the type referred to in which the die is swung from a material-receiving position to a position where it is pressed against a piece of work by treadle operated mechanism having a leverage to exert the desired pressure between the die and the 35 work and to provide the treadle of said mechanism with a pedal convenient for use by left-footed, right-footed or pedidextrous operatives.

To the accomplishment of these objects, the 40 features of the present invention consist in certain devices, combinations and arrangement of parts hereinafter described and then pointed out in detail in the appended claim which possesses advantages readily apparent to those skilled in the art.

The various features of the present invention 45 will be readily understood from an inspection of the accompanying drawings illustrating the best form of the invention at present known to the inventor, in which,

Figure 1 is a view in plan of the machine, herein shown, for purposes of disclosure, as an ink-marker;

Fig. 2 is a detail view in sectional elevation on the line 2—2, Fig. 3;

Fig. 3 is a detail view in longitudinal sectional elevation, and

Fig. 4 is a detail view in front elevation of the lower portion of the treadle showing the selected positions in which the pedal may be offset 5 laterally.

A machine such as is herein illustrated may be utilized for marking an ink line on an upper blank for use as a guide line in a subsequent 10 operation or for applying cement to many different sorts of work pieces. It will be described herein as utilized for applying ink lines to a vamp. When the machine is utilized for this particular purpose, it will be provided with an 15 applying die 5, (Fig. 3), which is mounted on a backing board 6. The backing board 6 is interchangeable with others carrying dies having different configurations, or capable of different uses, and is therefore detachably connected to a 20 cross-head or carrier 7 substantially in the manner illustrated and described in the patent to 25 Woodworth numbered 1,639,360 and dated August 16, 1927.

The carrier 7 is supported at the upper ends 30 of four parallel links comprising two forward links 8, (Figs. 1 and 3), and two rear links 9. The forward links are mounted on a horizontal shaft 10 journaled in the frame 11 of the machine which at one end supports an ink pad 12, (Fig. 3), and at the other end has a work table 35 13 upon which the work 14, (Fig. 1), to be marked is supported, it being understood that a gauge plate is interposed between the table and the work.

The rear links 9 are secured to a horizontal 40 shaft 15, (Figs. 1 and 3), journaled in the frame 11. Secured at the center of the shaft 15, (Fig. 3), is a gear 16 which meshes with a rack 17 cast integrally with a casting 18 secured to the front face of a yoke 19. In effect, the yoke 19 45 and the arms thereof consists the horizontal arm of a bell-crank lever 20 pivoted on a rod 21, the opposite ends of which are secured to the frame 11. The axis of the shaft 15 and the centerline of the rod 21 are mounted in the same horizontal plane. The rack 17 is formed on a curve, the center of which lies in the centerline of the rod 21. The vertical arm of the bell-crank lever 20 constitutes a treadle 22 having a pedal 23 carried by a jointed extension 24 thereof. 50

With this construction, a lever of the first-order is interposed between the foot pedal and the gear 16, so that a mechanical advantage is obtained through the depression of the pedal to permit the operative to exert the desired pres- 55

sure on the die when it is swung into engagement with the work.

By curving the rack 17 about a center lying in the centerline of the rod 21 which in turn is mounted in the same horizontal plane of the shaft 15, a smooth easy action is obtained through which the shaft 15 is rotated by the depression of the pedal 23.

In order to maintain the die 5 normally in engagement with the rubber pad 12, the treadle is connected operatively to the frame 11 by a coiled spring 25. When the operative depresses the pedal 23, the die 5 is swung from the position where it engages the ink pad 12 to a position where it engages the vamp 14 and deposits ink thereon to form the ink lines 26. When the pedal 23 is released, the spring 25 returns the die to the ink pad.

Experience has demonstrated that of the operatives of this type of machine, some are left-footed, some are right-footed and some are pedidextrous, the latter shifting from one foot to the other at will to relieve the strain on the legs. In order to accommodate the machine to these various characteristics, the jointed extremity of the treadle 22 is provided with a yoke 27 across the arms of which a pin 28 is rigidly mounted. The pedal 23, like a rubber-tread bicycle pedal, is rotatably mounted on a rod 29 projecting from a head 30 which is pivotally mounted on the

pin 28. With this construction, the pedal may be offset to the right or to the left to accommodate right-footed and left-footed operatives, respectively, the bottom of the yoke 27 serving as a stop to limit the movement of the pedal in either direction. Some girls are pedidextrous and appreciate being able to swing the pedal to the right in position for operation by the right foot and then, when the right leg tires, being able to swing the pedal to the left in position for operation by the left foot.

What is claimed as new, is:

In a machine for depositing material upon a work piece, a frame having a source of material supply at one end, and a work support at the other end, a material depositing die, a shaft journalled in the frame, parallel swinging links supporting said die, at least one of the links being secured to the shaft, a gear on the shaft, and means for rotating the shaft to swing the die from a position above the source of material supply to a position where the die contacts with a work piece on the support comprising a lever of the first order, pivoted from the frame, one arm of the lever having a curved rack engaged with the gear, the axes of the shaft and the lever lying in the same horizontal plane, the center of curvature of the rack lying in the axis of the lever.

LAURITS ANDERSEN. 30
